UNITED STATES PATENT OFFICE

1,972,237

SKIVING MACHINE

Eugene J. Ray, Beverly, Mass., assignor to United Shoe Machinery Corporation, Paterson, N. J., a corporation of New Jersey

Application May 10, 1933, Serial No. 670,327

6 Claims. (Cl. 69—9.5)

This invention relates to skiving machines and more particularly to machines of this kind adapted to operate upon small pieces of leather, such as parts of shoes, bags, or leather novelties, and in which a rotary skiving knife of tubular shape having a cutting edge at its end is used, although certain features of the invention are not necessarily limited to machines of this kind.

An object of the present invention is to provide a mechanism operating in an improved manner for producing a true circular cutting edge on the knife, which mechanism may be substituted, in machines of the above type, for existing mechanisms, without the necessity of otherwise changing or modifying such machines.

Another object of the invention is to provide a grinding device which is normally held out of contact with the knife and which may be brought manually into grinding contact with a surface of the knife to true up and sharpen its cutting edge, when necessary, and which may be adjusted, prior thereto, to bring the operating face of the grinding wheel into alignment for such grinding contact.

Another object of the invention is to provide an improved grinding device in which the grinding wheel will be rotated by grinding contact with the knife and which may be utilized to hone or grind a surface on one side of the cutting edge of the knife after the other surface, which cooperates to form the cutting edge, has been beveled by another grinding mechanism.

With the above objects in view, the several features of the invention consist in certain novel features of construction, combinations, and arrangements of parts, hereinafter described and claimed, the advantages of which will be obvious to those skilled in the art, upon a consideration of the attached drawing and the following description.

In the accompanying drawing,

Fig. 1 is a perspective view of a portion of a skiving machine showing a tubular skiving knife and the grinding attachment of the present invention;

Fig. 2 is a horizontal sectional view of the grinding mechanism of the present invention, portions of such mechanism being shown in plan, and showing the relation of the mechanism to the skiving knife and its driving shaft and mounting;

Fig. 3 is a vertical section of the grinding wheel spindle bearing bracket, with the spindle and wheel shown in elevation in normal position relatively to the skiving knife, dash lines in-

dicating the position of the wheel behind the knife after grinding contact has been established by bodily movement of the wheel; and

Fig. 4 is a detail in side elevation, partly in section, showing a releasable stop which normally retains the grinding device out of grinding contact with the knife but which is releasable to permit the removal of the device when necessary for changing the grinding wheel or for any other purpose.

The present invention is illustrated as embodied in a skiving machine of the general type disclosed in the United States patent to Alexander No. 1,117,541, granted November 17, 1914, to which reference should be made for a complete description of the machine and its operation.

The rotary tubular skiving knife of the machine is indicated by the reference numeral 10 and is clearly shown in Fig. 1, where the hinged portion of the casing, which covers and protects the knife and other portions of the mechanism, has been removed in order that the present invention may be seen in relation to the machine. The knife is clamped against the cylindrical inside surface of a knife holder 12 by an expanding clamping ring 14 which is expanded by drawing a clamping plate 16 within the knife 10 by means of a clamping rod 18 and a rod 20 threaded into said rod 18. An adjustable stop collar 22 is threaded on a cylindrical portion of the clamping ring 14 to serve as an abutment for the knife to position it axially in the machine. The knife is rotatively driven by a hollow knife shaft 24 which surrounds the rods 18 and 20 and on which shaft the knife holder 12 is mounted. This mounting of the skiving knife is fully illustrated and described in United States Letters Patent to Latham No. 1,342,120, granted June 1, 1920, to which reference may be made for further details.

A beveled surface 26 is maintained on the outer surface of the knife 10 by an external grinding wheel 30, shown diagrammatically in Fig. 1 and which may be brought into operation at the will of the operator, as fully described in the above-mentioned patent to Alexander.

The frame 40 of the machine, as it has been manufactured for some years, has been provided with a semi-cylindrical boss 42 having a bore 44 which is parallel to the axis of the knife shaft 24 and this bore has been utilized heretofore for supporting a grinding device of the type shown and described in United States Letters Patent to Latham No. 1,266,027, dated May 14, 1918, upon which the present invention is an improvement. In order to utilize this bore in the machine frame for

the grinding device of the present invention, a bushing 50 is provided which may be clamped in the bore by a clamping screw 52. Referring particularly to Fig. 2, this bushing has a bore 54, extending from one end to the other thereof, which bore is located in a horizontal plane but which is displaced from parallelism with the knife shaft 24 at a small angle indicated at "A", this angle in practice being preferably about 2°. In this bore 10 is a stud 56 for supporting the improved grinding device of the present invention, this stud being urged to the left (in Fig. 2) by a yielding spring 58. On the outer end of the stud 56 is a transverse socket 60, the under side of which has a flattened surface 62 for engagement with a surface 64 on an extension 65 of the bushing 50. The surfaces 62 and 64 cooperate to prevent the stud, and the hereinafter described grinding mechanism carried thereby, from turning about the axis 20 of the stud but they permit movement of the same longitudinally. To limit this longitudinal movement, against the urge of the spring 58, a releasable stop is provided in the form of a flat spring 66 which is secured to the extension 65. When 25 the spring or stop 66 is depressed, the stud and its associated parts, i. e., the entire grinding device, may be removed from the machine.

Mounted for longitudinal adjustment in the socket 60 is the integral shank 70 of a bearing bracket 72. The shank 70 is provided with a reduced portion 74, the outer end of which is threaded at 76 and passes through a hole in the end of the socket. A yielding spring 78 is seated between this end of the socket 60 and the shoulder formed 35 by the reduced portion of the shank. This spring forces the bracket toward the axis of the knife but such movement is prevented by a nurled adjusting nut 80 on the threaded portion 76 of the shank. This arrangement provides means for readily adjusting the shank longitudinally of the socket. Rotation of the shank in the socket is prevented 40 by a stud key 82 which extends from the shank 70 and fits a slot 84 cut in the side of the socket 60. The bearing bracket 72 provides a mounting for a spindle 86 on which the grinding or honing wheel 88 is mounted. The grinding wheel is secured to the spindle by a nut 90 which forces the wheel against a collar 92 on the spindle. Seated in a 45 recess in the bracket 72 is a ball thrust bearing 94 to take the end thrust that is transmitted to the collar 92 by the grinding wheel when it is being operated. A collar 96 is secured to the opposite end of the spindle 86 and prevents longitudinal movement of the spindle in the bearing bracket 72.

50 Before using the device of the present invention, the beveled edge 26 of the skiving knife 10 is ground by the grinding wheel 30, as described in the prior patents referred to herein. This grinding operation leaves a burr on the inside surface 60 of the knife and the purpose of the present device is to remove this burr and to grind the inside cylindrical surface of the knife 10 on a slight bevel so as to produce a true and sharp circular cutting edge that is concentric with the knife shaft 24 and which lies in a plane exactly perpendicular to said shaft. An additional advantage of this 65 procedure is that the cutting edge of the knife is formed of steel which originally was slightly below the outside surface or "skin" of the knife where the quality of the steel is not subject to the variations that commonly occur in the "skin".

The operation of the device in grinding the inside surface of the knife in the above manner will now be described. The operator presses 70 75 against the socket 60 which causes a movement of

the bearing bracket 72 and the grinding wheel 88 toward the knife, the spring 54 yielding to permit such movement. When first put into use, the grinding wheel 88 is adjusted, by means of the nurled adjusting nut 80, so that, as this movement is continued, the wheel 88 will clear the inside surface of the knife. The nut 80 is then adjusted slowly as the socket 60 is moved in and out until suitable grinding contact has been made with the revolving knife and the inside surface of the knife has been ground around its entire circumference to produce the slight bevel at the angle "A" with the inside cylindrical surface of the knife. When the knife has been sufficiently ground or honed, the transverse socket 60 is released and it is returned by the spring 54 to inoperative position, with the socket in contact with the stop spring 66. The grinding wheel 88 is now clear of the knife and will not interfere with it while the usual skiving operations are being performed. When the knife again becomes dull, the bevel 26 is ground by the grinding wheel 30 and then the wheel 88 is again brought into contact with the knife, after the nut 80 has been adjusted slightly to suitably re-position the 100 grinding wheel for grinding contact with the knife.

It is only necessary to depress the stop spring 66 slightly and the entire device may be completely removed from the machine. This is only 105 necessary when the grinding wheel is to be changed or adjusted, or when it may interfere with certain special types of work.

Having thus described my invention, what I claim as new and desire to secure by Letters 110 Patent of the United States is:—

1. A skiving machine having, in combination, a skiving knife, a grinding wheel, a spindle supporting the wheel with its peripheral face in position to be brought manually into grinding 115 contact with one surface of the knife, means normally tending to move said face out of contact with said surface, and adjustable means for aligning said face and said surface for grinding contact.

2. A skiving machine having, in combination, a tubular skiving knife, a driving shaft for the knife, a spindle, a grinding wheel mounted on the spindle, and means for guiding the grinding wheel in a path at a slight angle to the shaft to bring 125 its peripheral face into and out of grinding contact with a surface of the knife.

3. A skiving machine having, in combination, a tubular skiving knife, a driving shaft for the knife, a spindle, a grinding wheel mounted on the spindle, adjustable means for aligning the peripheral face of the wheel for grinding contact with a surface of the knife, and means for guiding the grinding wheel in a path at a slight angle to the shaft to bring said face into and out of 130 grinding contact with said surface of the knife.

4. A skiving machine having, in combination, a tubular skiving knife, a grinding wheel having its peripheral face arranged to be brought into grinding contact with the inner surface of the 140 knife, and means for supporting the grinding wheel with its axis of rotation inclined at a substantial angle to the plane of the knife edge.

5. A skiving machine having, in combination, a tubular skiving knife, a driving shaft for the 145 knife, a spindle, a grinding wheel mounted on the spindle, means for supporting the grinding wheel with its axis of rotation inclined at a substantial angle to the plane of the knife edge, and means for guiding the grinding wheel in a path 150

at a slight angle to the shaft to bring its peripheral face into and out of grinding contact with a surface of the knife.

6. A skiving machine having, in combination, 5 a tubular skiving knife, a driving shaft for the knife, a machine frame, a stud slidably mounted in the frame at a slight angle to the shaft and beyond the outer circumference of the knife, said stud having a transverse socket at its outer 10 end, a bearing bracket having a shank, said shank being mounted in the socket for yielding longitudinal movement, a spindle rotatably

mounted in said bearing bracket, a grinding wheel on said spindle and positioned so that its peripheral face will engage a surface of the knife at a substantial angle upon manual sliding of the stud in the frame, spring means to move the wheel out of engagement with said surface, a stop to limit such movement of the wheel, and an adjustable stop to limit the movement of said shank in said socket and thereby accurately align said face and said surface for grinding contact. 80 85
